UNITED STATES PATENT OFFICE.

CLINTON E. WILDER, OF ERIE, PENNSYLVANIA.

LATHE ATTACHMENT FOR TURNING AND FINISHING CRANK-SHAFTS.

1,098,654.

Specification of Letters Patent.

Patented June 2, 1914.

Application filed February 13, 1913. Serial No. 748,138.

To all whom it may concern:

Be it known that I, CLINTON E. WILDER, a citizen of the United States, residing at Erie, in the county of Erie and State of Pennsylvania, have invented certain new and useful Improvements in Lathe Attachments for Turning and Finishing Crank-Shafts; and I do hereby declare the following to be a full, clear, and exact description 10 of the invention, such as will enable others skilled in the art to which it appertains to make and use the same, reference being had to the accompanying drawings, and to the letters of reference marked thereon, forming 15 part of this specification.

My invention relates to machines adapted to turn and grind crank-pins, and has for its object the provision of mechanism adapted to be removably mounted upon an ordinary 20 lathe, by means of which the crank-pins, or wrist-pins, of multiple crank-shafts can be turned or ground without the necessity of changing the position of the crank-shaft in the lathe, when changing the tool from one 25 crank to another.

The features of my invention are herein-after fully set forth and described and are illustrated in the accompanying drawings, in which:—

30 Figure 1, shows a side elevation of my improved wrist-pin turning mechanism, in place on a lathe. Fig. 2, is a front elevation of the same, looking in the direction of the arrow in Fig. 1. Fig. 3, is a vertical, central section of the same. Fig. 4, is a rear view, looking in the direction of the arrow z , in Fig. 1. Fig. 5, is a horizontal section of the same, on the line $x-x$, in Fig. 4, looking downward.

40 In these drawings, A, indicates the lathe-bed, A', the face-plate, and A², the tail-stock of turning or grinding lathe, which parts are of general and ordinary construction. Within the face-plate A', and tail-stock A², 45 I insert a journal-pin, A³, (see Figs. 3 and 5), of conical shape, to fit the central openings in the face-plate A', and tail-stock A². The journal-pins A³, are provided with a collar, a and with a cylindrical portion A⁴, (see Fig. 3), and with a screw-threaded stud a' . Upon the cylindrical portion A⁴, I mount my improved crank-shaft fastening, which consists of the frame B, having a hub B', which fits upon the portion A⁴, of the journal-pin. This frame B, is provided with a counterweight arm B², and with slide-ways

B³, and is provided with a slot B⁴, and with the slots B⁵, (see Fig. 4). Upon the face of this frame B, I place a sliding member C, which fits in between the slide-ways B³, of the frame B, and is provided with a rearwardly projecting portion C and C², which extends rearwardly through the slot B⁴, in the frame B'. The front of the member C, is provided with a circular index plate C³, 60 within which plate I make a depression c , and a central opening c' , which opening c' , extends from said depression c , backwardly through the member C. Upon the face of the index-plate C³, I place an index clamp-plate D, which has a circular projection d on the rear side thereof, adapted to fit into the depression c , in the index-plate C³. This index clamp-plate D, is also provided with a central opening therethrough, through 70 which opening and the opening c' in the member C, I place a clamp-bolt E, which bolt is provided with a nut e , by means of which the index-plate C³, and the index clamp-plate D, may be firmly clamped together. Upon the face of the index clamp-plate D, I integrally form one half of a shaft-gripping vise F, which is provided with a semi-circular recess concentric with the bolt E, and hinged upon one end of this 75 vise-jaw F, by means of the pivot f , I place another vise-jaw F. For clamping these jaws upon a shaft G, I provide a bolt H, one end of which is pivoted in the lower jaw F, by means of the pivot f' , and the other end 80 of said bolt extends upwardly through the slot f^2 , in the free end of the jaw F', and is provided with a nut H' by means of which the swinging jaw F' may be clamped upon a shaft G, when desired.

To secure the frame B, upon the journal-pin A⁴, I place a screw-collar a^2 upon the screw-stud a' . To prevent dust and dirt from entering about this journal pin I provide a plate a^3 which is secured to the frame 90 B, by means of the screws a^4 .

In order to give radial adjustment to the member C and the mechanism secured thereon, I provide a screw J, which extends inwardly from the frame B, through a screw-threaded opening in the arm C', and is provided with a collar J' to prevent longitudinal movement thereof.

To provide for the rotation of the index clamp-plate D, upon the index-plate C³, and to control the same, I provide openings K, 110 in the index-plate, which correspond with

the centers of the wrist-pin G' , in the crank-shaft G , to be ground, and I provide the index clamp-plate D , with a sliding bolt L , adapted to enter the openings K , in the index-plate C^3 , as the index clamp-plate D , is rotated thereon, and stop the rotation thereof at the required points. This sliding bolt L , is provided with a spring l , to hold the same normally in a forward position, and 10 with a head l' , by which it may be withdrawn, and a stud l^2 , which may be turned to engage the shoulder l^3 , to retain said bolt L , out of engagement with the index-plate C^3 , when desired. I also provide clamp-bolts M , which extend through the slots B^5 , in the frame B , into the member C , by means of which the slideable member C , may be firmly clamped to the frame B , after it has been adjusted to the proper position by the 15 operation of the screw J . On the counter-weight arm B^2 , I place sufficient counter-weight N , to balance the mechanism hereinbefore described and work clamped therein during the operation of the machine.

20 In order to secure perfect parallelism between the members placed on the face-plate A' , and the tail-stock A^2 , I provide in the weight arm B^2 , a stop-opening O , and I secure upon the lathe-bed A , stop-supports P , 25 in which I place sliding bolts P' , which are adapted to be pressed forward and extend into the opening O , in the arm B^2 , of each of the members, and hold them in exact parallelism during the removal of a shaft G , 30 from the clamping-jaws F , and F' , and the placing of another shaft therein and clamping the same. The member placed upon the journal-pin of the face-plate A' , is caused to rotate with said face-plate by means of 35 a strap Q , (see Fig. 4), one end of which is bolted to the arm B^2 , by means of a bolt q , and the other end of which is bolted to the face-plate A , by means of a bolt q' , so that 40 the two bodies will rotate in unison.

45 In operation, the crank G , is placed in the vises $F-F'$, and one of the cranks G' , thereon, turned therein until it is in proper alinement with the center of rotation, as indicated by the broken line R , in Fig. 1, in 50 which position the shaft G , is firmly clamped by means of the nut H' , and bolt H , at each end of the shaft. Then after the first crank-pin G' , has been finished, the sliding bolt L , is withdrawn from its index opening 55 K , in the index-plate C^3 , the clamp-nut e , is loosened, and the crank-shaft G , together with its clamping-jaws F , and F' , and the index clamp-plates D , at each end thereof, are rotated until the spring-pressed sliding 60 bolts L , enter the next successive stop opening K , which will bring another one of the crank-pins G' , in line with the center of rotation, as indicated by the broken line R ,

in Fig. 1, when the clamp-nuts e , are again tightened up, and the process of grinding or 65 turning the crank-pin G' is again repeated. This operation is repeated for each crank-pin in the crank-shaft.

Fig. 1, of the drawings does not show a cutting or grinding tool in position thereon, 70 but it is obvious that any of the well known forms of such tools could be used with my improved mechanism.

Having thus fully shown and described my invention, so as to enable others to construct and operate the same, what I claim as new and desire to secure by Letters-Patent is:—

1. The combination in a device of the class described, of a face-plate, a tail-stock, journal-pins therein, arms mounted on said journal-pins, slide-ways on said arms, a radially slideable member mounted in said slide-ways, means to secure said slideable member in adjusted position in said slide-ways, clamp-jaws rotatably mounted on said radially slideable member, means to stop the rotation of said clamping-jaws upon said slideable member, and means to cause said arms to revolve upon said journal-pins in unison with 90 said face-plate, substantially as set forth.

2. The combination in a device of the class described, of a face-plate, a tail-stock, journal-pins therein, arms mounted on said journal-pins having slots therein, slide-ways on 95 said arms, a radially slideable member mounted between said slide-ways, an arm on said slideable member extending through one of said slots, an adjusting screw engaging said arm, clamping-bolts in the other of said 100 slots to secure said slideable member in adjusted position, clamp-jaws pivoted on said slideable member, means to stop the rotation of said clamp-jaws upon their pivot at predetermined points, and means to cause said 105 arms to rotate upon said journal-pins, substantially as set forth.

3. The combination in a device of the class described, of a face-plate, a tail-stock, journal-pins therein, clamping-jaws mounted on said journal-pins upon independent axes eccentric to said journal pins, means to stop the rotation of said clamp-jaws upon their own axes at predetermined points, means to adjust the axes of the clamp-jaws 110 mounted upon said journal-pins in parallelism to each other, and means adapted to cause said clamp-jaws to revolve upon said journal-pins in unison with said face-plate, 115 substantially as set forth.

In testimony whereof I affix my signature, in presence of two witnesses.

CLINTON E. WILDER.
